LIQUID WAX APPLICATOR

Elonza A. Pennington, Arkadelphia, Ark.

Application August 21, 1953, Serial No. 375,672

1 Claim. (Cl. 15—131)

This invention relates to an applicator, and more particularly to a liquid wax applicator.

The object of the invention is to provide a liquid wax applicator which will facilitate the waxing of floors, linoleums and the like, the present invention including a novel manually operable valve means for controlling the dispensing of the wax from its reservoir.

Another object of the invention is to provide a liquid wax applicator which includes a pivotally mounted handle that can be adjusted or moved to any desired angle, there being a mechanism on the handle for controlling the dispensing of the wax from the reservoir.

Another object of the invention is to provide an applicator which can be used for applying various liquids to floors and the like, and wherein such applicator can be used for dispensing or applying shellac, varnish, or paint, the present invention permitting floors to be waxed or otherwise treated in a minimum amount of time and with a minimum amount of effort.

A further object of the invention is to provide a liquid wax applicator which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a perspective view of the liquid wax applicator, constructed according to the present invention.

Figure 2 is a top plan view of the liquid wax applicator.

Figure 3 is a sectional view taken on the line 3—3 of Figure 2.

Figure 4 is a sectional view taken on the line 4—4 of Figure 3.

Figure 5 is an enlarged fragmentary sectional view showing certain constructional details of the invention.

Figure 6 is a sectional view taken on the line 6—6 of Figure 5.

Figure 7 is a sectional view taken on the line 7—7 of Figure 3.

Figure 8 is a sectional view taken on the line 8—8 of Figure 3.

Figure 9 is a fragmentary sectional view showing a modification wherein the sponge can be secured by a bolt and nut assembly to the base of the applicator.

Figure 10 is a perspective view of the plunger.

Figure 11 is a perspective view of the valve block.

Referring in detail to the drawings, the numeral 10 designates a hollow tubular handle which can be made of any suitable material such as metal, and secured to the upper rear end of the handle 10 is an enlarged neck 11. A tubular hollow sleeve 12 is seated in the neck 11 and secured thereto in any suitable manner, as for example by welding. The sleeve 12 is provided with a cutout 14. Extending through the cutout 14 is a trigger 16, the trigger 16 being pivotally connected to the sleeve 12 by a pin or bolt and nut assembly 15, Figure 3.

Secured to the front end of the handle 10 is a pair of

2

arms 21, Figure 2, and the arms 21 are pivotally connected to a valve block 22 by means of a pin or bolt and nut assembly 23. The pivotal connection 23 permits the handle 10 to be adjusted or moved to any desired angular position so that the liquid wax applicator can be used with comfort and ease.

There is further provided a container or tank 25 which is provided with a bottom portion 26. A filling cap 27 is arranged on the upper end of the container 25, and the cap 27 is provided with a vent opening 28. The bottom portion 26 is provided with a discharge opening 29. The opening 29 is arranged in registry with an opening 30 in the valve block 22, and the opening 30 communicates with a chamber or bore 31. Communicating with the bore 31 is an opening 32, and the opening 32 is arranged in registry with an opening 33 in a base 34, Figure 4. Suitable screws or bolts 35 are provided for interconnecting the base 34, block 22 and container 25 together.

Detachably connected to the base 34 is one or more sponges 38. For maintaining the sponges 38 contiguous to the lower surface of the base so that the wax can pass onto the sponges 38, a pair of flanges 36 depend from the base 34, and the flanges 36 each have their lower ends terminating in inturned lips 37, Figure 5, the lips 37 frictionally engaging the sponges 38 to prevent accidental disengagement of the sponges from the base. The sponges can be used for applying or spreading the wax on the floors, linoleum, or other structures.

A valve means is provided for controlling dispensing or discharge of the wax onto the sponges, and this valve means comprises a plunger or piston 39 which is slidably or reciprocably arranged in the bore 31. The plunger 39 is mounted for movement into and out of closing relation with respect to the openings 30 and 32. In Figure 3 the plunger is shown in closed position so that no wax can flow from the container, and in Figure 5 the plunger is shown in retracted position so that wax can flow from the container 25 onto the sponges 38 for application to the floor. For retracting or moving the plunger 39 to open position, a finger 40 is pivotally connected to the block 22 by means of a pin 41. The finger 40 extends through a slot or cutout 42 in the plunger 39. A clamp 43 is pivotally connected to the finger 40 by means of a pin or bolt and nut assembly 45, the bolt and nut assembly 45 extending through one of a set of openings 44 in the finger. A set screw 46 extends through a portion of the clamp 43 for connecting the cable 19 to the clamp 43, the cable 19 being trained over the pulley 18 mounted on the pin 17. The other end of the cable 19 is connected to the inner end of the trigger 16 through the medium of an opening 20, Figures 3 and 7.

A means is provided for urging or biasing the plunger 39 to its closed position, and this means comprises a cap 47 which is secured to the block 22 by suitable screws 48, Figures 2 and 5. A coil spring 49 is positioned in the cap or casing 47, and the coil spring 49 is interposed between the cap 47 and the adjacent end of the plunger 39.

Referring to Figure 9 of the drawings there is shown a slightly modified form of the invention wherein a modified method of attaching the sponge 51 to the base is provided. Thus, in Figure 9 the numeral 51 designates the sponge and a suitable strip of material 50 may be secured to the upper surface of the sponge 51. Bolts 52 may extend from the strip 50 and may be secured thereto, and the bolts 52 can extend through suitable openings 53 in the base 34. Nuts 54 may be arranged in threaded engagement with the bolts 52 for maintaining the sponge firmly attached to the base.

As shown in Figures 6 and 9 and in Figure 4, the block 22 may be provided with recesses or hollowed out portions 55 to reduce the weight thereof. It will be seen

from the drawings that the plunger 39 is provided with an opening 13, and when the opening 13 registers with the openings 30 and 32 the wax will be permitted to flow from the container onto the sponges. However, when the opening 13 in the plunger 39 is out of registry with these openings, then no wax will be able to flow onto the sponges.

From the foregoing it is apparent that a liquid wax applicator has been provided wherein a predetermined quantity of wax from the container 25 can be dispensed onto the sponges 38 for application to the desired surface. In use the cap 27 is removed and the container 25 is filled with the desired quantity of liquid wax. Then, the sleeve 12 and handle 10 may be gripped and can be pivoted to any desired angle due to the pivot pins 23. When it is desired to dispense some of the wax from the container 25, it is only necessary to manually squeeze or pivot the pin or trigger 16 to cause the cable 19 to be placed under tension. As the cable 19 is actuated the finger 40 will be pivoted about the pin 41 to thereby move the plunger 39 from the position shown in Figure 3 to the position shown in Figure 5 whereby wax will flow from the container 25 through the registering openings and onto the sponge 38. As long as the trigger 16 is actuated the liquid wax will continue to flow from the container onto the sponges. When pressure is released on the trigger 16 the coil spring 49 will bias or move the plunger 39 back from the position shown in Figure 5 to the position shown in Figure 3 so that no further wax will be dispensed.

The construction of the valve mechanism and handle permit the valve to be actuated regardless of the position the handle is in. The present invention is fast in operation and can be used as a scrub mop by using other liquids besides wax in the container 25. The sponge may be made of one piece or may be made as a plurality of separate pieces, and the sponges can be easily removed for cleaning. The ends of the sponge may project beyond the ends of the base 34 as shown in Figure 2 so as to prevent the ends of the base from scratching walls and the like. The cable 19 can be made of a piece of wire 40 connected to a piece of string and an inspection plate 9 may be provided on the sleeve 12.

I claim:

In a liquid wax applicator, a hollow tubular handle provided with an enlarged rear neck, a tubular hollow sleeve seated in said neck and provided with a cutout intermediate its ends, a trigger pivotally mounted intermediate its ends in said sleeve and having a finger engaging end portion projecting through said cutout, a pin supported by said sleeve behind said trigger, a pulley rotatably supported on the pin in said sleeve, a cable trained over said pulley and connected to the inner end of said trigger, a pair of spaced apart arms secured to the front end of said handle, a block pivotally mounted between said arms, said block being provided with a plurality of recesses to reduce the weight thereof, a container for liquid wax having a bottom portion secured to the top of said block, a base secured to the lower surface of said block and provided with a pair of parallel depending flanges having opposed inturned lips, a sponge detachably mounted between said flanges, there being registering openings in said base, block, and bottom portion of said container, valve means controlled by said trigger and cable for controlling passage of liquid wax through said openings, said valve means comprising a plunger reciprocably arranged in said block and provided with a transverse slot, a finger projecting through said slot and having its lower end pivotally connected to said block, a clip pivotally connected to the upper end of said finger and connected to said cable, and means for normally maintaining said valve means in closed relation with respect to said openings, said last named means comprising a cap secured to said block, and a coil spring interposed between said cap and the adjacent end of said plunger.
